SLIDE CORE TUNING DEVICE

Theodorus Antonius Spoor, Eindhoven, Netherlands, assignor, by means assignments, to Hartford National Bank and Trust Company, Hartford, Conn., as trustee

Application April 23, 1946, Serial No. 684,401
In the Netherlands April 4, 1942

Section 1, Public Law 690, August 8, 1946
Patent expires April 4, 1962

4 Claims. (Cl. 171—242)

1

This invention relates to a slide core tuning device i. e. a tuning device whose adjustment to various frequencies of a certain range of frequencies is effected by engaging a core consisting of so-called high-frequency iron which extends to a greater or lesser extent into the space surrounded by the winding of the coil and more particularly to a device of this kind in which the driving member for moving the slide core engages the core at the height of a part of the core itself.

In devices of this kind, which are constructed in a known manner, the total length is much greater than the length of a coil having a stationary iron core, due to the space which must remain available for moving out the core.

The present invention has for its object to provide a slide core tuning device whose size is reduced to a minimum so that the total length only slightly exceeds the length of a corresponding coil having a stationary iron core.

In a device of the said kind this purpose is attained, according to the invention, since in the moved out position the core mainly stays in the foot of the device, which foot carries the coil, the shielding means thereof, the driving device for the slide core and the terminals, the height of the foot being matched to the length of the slide core.

In this way it is ensured that the space required at any rate for leading the coil connections through the foot of the coil and for the customary soldering tags is also utilized for providing the space for the core in the moved out position. In a suitable form of construction a hollow column is positioned on the base of the foot, which column supports the coil former and in which moves the slide core. Moreover, the shaft of a pinion is journaled in the column in the vicinity of the end of the coil, which pinion meshes with a gearing provided on the core. The advantage of this construction consists in a very stable assembly of driving means and bearings of the slide core associated with a compact mounting.

It is known per se to readjust the inductance of an iron core coil by shifting the iron core which is provided with teeth engaging the teeth of the pinion which can be rotated for re-adjusting the inductance.

When making use of the present invention preferably one of the bearings of the pinion is given a conical shape and placed in the immediate proximity of the pinion, thus avoiding beforehand play in the bearing.

In other well-known constructions of such slide core tuning devices the core is driven by means of an extension so that after the shielding means

2

have been arranged about the coil a correction of the position of the iron core relatively to the coil is still possible. In order that with constructions according to the invention, in which no elongation of the core projects from the shielding means, such adjustment may be possible after the shielding means have been provided the shielding box is, according to the invention, provided with an aperture through which the pinion can be mounted and driven. the shielding means extending to the base of the foot, and the part of the shaft of the pinion co-operating with the conical bearing being caused to engage this bearing by a plate spring which can be introduced from the bottom side of the foot. In this way the pinion can still be adjusted relatively to the iron core after mounting the shielding means.

In a suitable form of construction of a device according to the invention the hollow column 20 extends through the base of the foot of the coil beyond the bottom thereof at which height are provided also the coil connections. Thus the available space in the coil construction is utilized as much as possible.

According to the invention, in order to secure a suitable guiding of the iron core and a driving without back lash the end of the core first entering the coil case is preferably led through the interior of the coil case at the same side of the core where the driving member is provided and is caused to engage the said guiding and the driving member by a spring member provided at the other side of the core between the driving device and the said end.

The spring member may be constituted with advantage by a pressure roller which by means of a spring provided adjacent the column is caused to engage the core through a slit in the column. This form of construction also contributes to the obtainment of a very compact assembly.

According to the invention, for exactly adjusting the position of the coil relatively to the iron core use may be made with success of the construction in which the coil case, at the side where it is not supported by the foot, is so secured to the top of the shielding means as to be adjustable in a longitudinal direction.

The invention will be more fully explained by reference to the accompanying drawing, in which 50 Figures 1 and 2 represent partly in elevation, partly in section the foot of a slide core tuning device according to the invention in two directions.

Figure 3 is a plan view of the foot, Figure 4 55 being an elevation of the driving pinion and Fig-

ure 5 illustrating the attachment of the coil case to the shielding box.

Figure 1 shows a coil former 1 about which are provided the turns 2. This coil former is supported by the foot 11 of the coil which also carries the shielding box 25 and the driving device which will be described more in detail hereinafter. In order that the inductance of the turns 2 may be adjusted the coil former 1 contains a core 13 of high-frequency iron which can be moved to and fro therein. The driving of this slide core is effected by providing the core with a rack 16 engaged by the teeth of a pinion 36.

The pinion 36 is provided at the side of the coil where the core enters the coil.

On the base of the foot is positioned a hollow column 12 which constitutes the support proper of the coil case and within which moves the slide core, this column containing at the same time the bearings for the shaft of the pinion 36. The column extends through the base 41 of the foot 11 of the coil beyond the bottom of the foot at which height are also provided the terminals 23 of the coil.

In order to support the coil former 1 the column 12 is provided with a vertical cylindrical aperture 14 exactly engaged by the coil former 1. The slide core 13, which has a circular cross-section, is provided at the top with a guide cam 19 which passes over the inner wall of the coil former. The teeth of the slide core are caused to engage the teeth of the pinion 36 by means of a pressure roller 17 and a spring 18, for which purpose a slit 42 is provided in the column, the mounting being such that the pressure roller 17 is provided at the side of the slide core remote from the pinion 36 and the cam 19 and is caused to engage the core between these two parts. By the action of the pressure roller and the spring the teeth of the core are caused to engage those of the pinion 36 on the one hand, whereas on the other hand the cam 19 steadily remains in mechanical contact with the inner wall of the coil former 1. In this way it is ensured that no play can occur in the driving between the pinion and the gearing of the core. In order that the pinion 36 itself may also be so journalled as to be free from play use is made of the construction shown in Figures 2 and 4, in which the pinion in the immediate vicinity of the gearing is furnished with a conical part 20 which cooperates with a conical gearing 43, the pinion being steadily caused to engage this conical bearing by a spring 22.

As a rule it is desirable that the position of the iron core should be adjustable relatively to the turns after the shielding box has been placed over the coil. Since in the construction according to the invention the iron core is not accessible from the exterior the following construction is proposed. The shielding box is provided with an aperture through which the pinion can be mounted and driven, and the plate spring 22 having to press the part of the pinion shaft cooperating with the conical bearing against the latter can be introduced from the bottom side through the foot so that the pinion can be provided after the shielding means have been mounted.

As appears from Figure 3 this yields the advantage at the same time that the diameter of the shielding box can be made smaller than in the case of a construction in which the pinion is mounted before the shielding box.

In Figure 3 a portion of the pinion shaft extends through the shielding means, which is not

possible if the shielding box is to be provided last. It will be obvious that the position of the pinion relatively to the core can be altered after providing the shielding means.

The pinion 36 is provided with a concentric bore 27 and at one side with a cam 26 so that the pinion can be driven by means of a shaft which may be led through the bore 27. This shaft may have secured to it a carrier which cooperates with a cam 26 for rotation of the pinion. When it is desired simultaneously to drive a plurality of tuning devices according to the invention the latter are arranged one behind the other in such manner that the bores 27 of the various pinions lie as exactly as possible in a straight line, whereupon a thin shaft is successively passed through the various pinions which shaft is provided at the required points with carriers co-operating with the cams 26.

Figure 5 represents schematically how the side of the coil case 1, which is not supported by the foot, is secured to the top 45 of the shielding box in such manner that the coil case can be shifted in a longitudinal direction. To this end the coil case is provided at the top with a flange 46 and a threaded portion 47 engaging an aperture provided therefor in the upper wall 45. Between the flange 46 and the inner side of the wall 45 is provided a slightly curved spring 48 which tends to lower the coil case. By turning a nut 49 fitting on the screw thread 47 the distance of the top of the coil to the upper wall of the shielding means and consequently the position of the coil relatively to the iron core can be adjusted. Furthermore the coil body comprises at its top a hexagonal portion 50. The aperture made in the upper wall 45 is also hexagonal, thus preventing the coil from following the nut 49 on screwing down the latter.

4. I claim:

1. A slideable core inductance unit, comprising a supporting base provided with a tubular projection, a hollow column on the base having an aperture in the wall thereof, a tubular coil supporting member supported by the column, a coil wound on the coil supporting member, a shield member enclosing the coil and supported by the base, a toothed core slideable within said coil supporting member, a pinion gear for engaging the teeth on the core for moving the core into and out of the coil, the core in the out position being partially housed in the tubular extension of the base, a conical bearing operatively associated with the pinion gear, and a shaft extending through the aperture in the wall of the column and journalled in the conical bearing for controlling movement of the bearing.

2. A slideable core inductance device as claimed in claim 1, in which a spring is provided for axially urging the conical bearing to engage the pinion.

3. A slideable core inductance device as claimed in claim 1, in which the hollow column extends through the base and forms the tubular projection thereof and connecting terminals are provided on the base for the coil.

4. A slideable core inductance device, comprising a supporting base, a hollow column extending through the base having an aperture in the wall portion above the base, a tubular coil supporting member supported by the column above the base, a coil wound on the coil supporting member, a shield member enclosing the coil and supported on the base, a core slideable within the coil supporting member having a plurality

of gear teeth on one side thereof and a substantially free surface on the other side thereof, a pressure roller engaging the free surface of the core for applying pressure between the core and the coil supporting member, and gear means engaging the gear teeth on the core between the ends thereof for moving the core into and out of the coil supporting member, the core in the out position being partially housed in the extension of the column beneath the supporting base. 10
